UNITED STATES PATENT OFFICE.

JOHN G. WHILLDIN, OF PHILADELPHIA, PENNSYLVANIA, ASSIGNOR TO THE
WHILLDIN POTTERY COMPANY, OF SAME PLACE.

DESIGN FOR A FLOWER-POT.

SPECIFICATION forming part of Design No. 20,337, dated November 18, 1890.

Application filed October 21, 1890. Serial No. 368,875. Term of patent 7 years.

To all whom it may concern:

Be it known that I, JOHN G. WHILLDIN, a citizen of the United States, and a resident of Philadelphia, Pennsylvania, have invented a new and original Design for a Flower-Pot, of which the following is a specification.

My design for a flower-pot is clearly shown in the accompanying drawings, in which—

Figure 1 represents a flower-pot of my design in perspective, and Fig. 2 is an inverted plan view.

The main feature of the design is the peculiar shape of each foot projecting from the base of the pot.

C is the tapered body of the pot, having a flat base G, with the usual orifice therein. Projecting from this base are three or more feet

a a a, arranged equidistant from each other. Each foot is in the form of a half-disk, preferably slightly flattened at x, the outside line 20 of each foot following the line of the body portion of the pot.

I claim—

The design for a flower-pot, as herein described, and shown in the accompanying drawings.

In testimony whereof I have signed my name to this specification in the presence of two subscribing witnesses.

JOHN G. WHILLDIN.

Witnesses:

WILLIAM D. CONNER,
HARRY SMITH.
